US00D699359S

(12) **United States Design Patent**
Lindekugel et al.

(10) **Patent No.:** US D699,359 S
(45) **Date of Patent:** ** Feb. 11, 2014

(54) **ULTRASOUND PROBE HEAD**

(75) Inventors: **Eric W. Lindekugel**, Salt Lake City, UT (US); **Amir Orome**, Sandy, UT (US); **Matthew W. Bown**, West Bountiful, UT (US)

(73) Assignee: **C. R. Bard, Inc.**, Murray Hill, NJ (US)

(**) Term: **14 Years**

(21) Appl. No.: **29/428,649**

(22) Filed: **Aug. 1, 2012**

Related U.S. Application Data

(63) Continuation-in-part of application No. 13/206,396, filed on Aug. 9, 2011.

(57) **CLAIM**

The ornamental design for an ultrasound probe head, as shown and described.

DESCRIPTION

FIG. 1 is a front perspective view of an ultrasound probe head showing my new design;

FIG. 2 is a rear perspective view of the ultrasound probe head illustrated in FIG. 1;

FIG. 3 is a front elevation view of the ultrasound probe head illustrated in FIG. 1;

FIG. 4 is a first side elevation view of the ultrasound probe head illustrated in FIG. 1;

FIG. 5 is a bottom view of the ultrasound probe head illustrated in FIG. 1;

FIG. 6 is a rear elevation view of the ultrasound probe head illustrated in FIG. 1;

FIG. 7 is a second side elevation view of the ultrasound probe head illustrated in FIG. 1; and,

FIG. 8 is a top view of the ultrasound probe head illustrated in FIG. 1.

The broken lines are included for the purpose of illustrating portions of the ultrasound probe head that forms no part of the claimed design.

1 Claim, 3 Drawing Sheets
